UNITED STATES PATENT OFFICE.

WILLIAM H. BOMGARDNER AND HENRY KERNS, OF OMAHA, NEBRASKA.

CAR-BRAKE.

SPECIFICATION forming part of Letters Patent No. 240,370, dated April 19, 1881.

Application filed October 19, 1880. (No model.)

To all whom it may concern:

Be it known that we, WILLIAM H. BOMGARDNER and HENRY KERNS, of Omaha, in the county of Douglas and State of Nebraska, have invented a new and Improved Car-Brake, of which the following is a specification.

This invention relates to the automatic braking of railroad-cars in cases where they receive shocks from either end of the train.

10 The object of our invention is to provide a system of car-braking by which the brakes are set instantaneously by diminishing the speed of the engine, and by which they can be released by increasing the speed of the engine, 15 the object being further to set the brakes automatically whenever the moving or standing train receives a shock from either end, said system being so arranged as not to interfere with hand-braking as commonly applied.

20 Figure 1 is a side elevation of a car-truck with lower part of car, showing the improved brake device applied. Fig. 2 is a plan of the reverse of the car-bottom with improved device applied. Fig. 3 is end view of the same.

25 Fig. 4 is a side elevation of the cam-lever. Fig. 5 is a plan of the same. Fig. 6 is a side elevation, showing the lug and draw-head. Fig. 7 is a plan of the reverse of the same.

Similar letters of reference indicate corresponding parts.

30 In the accompanying drawings, A represents the spring-actuated draw-head, on which is fastened or formed a lug, B. A cam-lever, C, is loosely pivoted on a bolt, D, which is 35 screwed up into the frame A' of the car, so that the larger and rounded end of said cam-lever C bears against said lug B. The lower end of the pivot-bolt D is securely held by a brace, E, which is fastened, by means of 40 suitable bolts or screws, to a timber of the car A'. The lever C is provided with adjusting-holes *a a* for the reception of an end of the chain F, as shown, the other end of which chain F is made fast to the brake-rod G, which 45 is held to the frame A' of the car by suitable straps *b b*.

G' represents the brake-wheel, of ordinary construction.

The connecting-rod H connects at one of the 50 holes *a* with the cam-lever C, and at the other end with an end of the lever I at the rear end

of the car. Said lever I is held to the rear brake-beam, K, by forked rod and nut L. To the opposite end of the lever I is connected one end of the connecting-rod H', whose forward extremity is connected with the front 55 brake-beam, K', by forked rod and nut L'.

M represent the brake-shoes on the ends of the respective brake-beams K K'. The brake-beams K K' are held suspended from 60 the frame A' by hangers and straps N N, as shown.

A lever, O, is fulcrumed in the forked end of a rod, O', that is screwed up into the car-frame A', and the forked end of said lever O 65 embraces the pivot-bolt D, and, pressing up against the cam-lever C, holds the latter up in position for action, while the other end of said lever O is secured in the forked lower end of the rod P, that is extended upward and is secured to the frame A' by a suitable band, *c*. This rod P is provided with a forward projection, termed a "keeper," P', and also with a handle, P²; and secured to the frame A', in rear of and bearing against said rod P, is a spring, Q, 70 that holds said rod P out against the front of the band *c*.

When retrograde movement is applied to the draw-head A, when the engineer reverses the motion of or slackens the speed of the engine, 80 or in case of a collision in the front or rear of the train, the lug B presses against the free end of the cam-lever C, which turns on the pivot-rod D, which cam-lever C is moved through the means of the connecting-rods H 85 H', lever I, and brake-beams K K', to set the brake-shoes M M firmly against the car-wheels S S, with a force corresponding with the force applied to said draw-head A. As soon as the pressure on the draw-head A is relieved, which 90 occurs when the retrograde movement ceases, the brake-shoes M M will fall off from the wheels S S, being actuated thereto by the action of the spring *f* that encircles the rear of the draw-head A.

95 When it is desirable not to use the automatic brake device the operator will grasp the handle P² of the rod P and press the said rod P rearward with sufficient force to overcome the resistance of the spring Q. This movement will permit the keeper P' to pass between the car-frame A' and the holding-band *c*. The

operator will then lift the rod P, so that the lower end of the keeper P' will be above the band c, when he will release said rod P, which will be forced forward by the spring Q, so that the lower end of said keeper P' will rest on the band c and hold said rod P up. This movement of the rod P will depress the inner and forked end of the lever O to the brace E, and the cam-lever C will then drop, by its own weight, below the lower edge of the lug B, and so disconnect the automatic brake device from the draw-head A. If it is desired to again connect the improved brake device with the draw-head A, the movement of the rod P is reversed.

15 The parts indicated by the letters F G G' H H' I K K' L L' M N constitute the ordinary brake device, and can be readily operated whether the cam-lever C be connected or disconnected with the draw-head A.

Having thus described our invention, we claim as new and desire to secure by Letters Patent—

1. In car-brakes, a cam-lever, C, loosely pivoted and connecting the brake mechanism with a lug on the bottom of a spring-held draw-head, as and for the purpose specified.
2. The combination, with the cam-lever C, and rod D, of the lever O, rod O', rod P, provided with keeper P' and handle P², spring Q, and band c, substantially as herein shown and described, whereby said cam-lever C is disconnected from the draw-head A, as set forth.

WILLIAM HAMILTON BOMGARDNER.
HENRY KERNS.
